UNITED STATES PATENT OFFICE.

LOUIS F. UTZ, OF HAMILTON, OHIO, ASSIGNOR TO THE FREIBERG-SIMRALL COMPANY,
OF HAMILTON, OHIO, A CORPORATION OF OHIO.

STERILIZING AND WASHING MACHINE.

Application filed September 20, 1921. Serial No. 502,026.

My invention relates to machines for sterilizing glass tumblers, bottles, or other articles, and simultaneously washing them.

I am aware that there are numerous devices on the market for washing table-ware, glasses and the like, but so far as I am advised, there are no machines which accomplish in connection with the act of washing such articles the sterilizing of them for a 10 timed period necessary for complete safety against transmission of infection by the cleansed article.

Thus it is the object of my invention to provide a machine which will handle the 15 most fragile articles of glassware and retain them for a timed period in the presence of a sterilizing solution, after which several washings are given to the article to remove all traces of the sterilizing liquid.

20 It is also my object to provide a washing machine of strong and durable construction and effective mechanical operation, which will evenly carry the articles to be washed between a series of upper and lower spray heads, said mechanical arrangements being such that smooth operation is provided and furthermore a drying chamber is included which results in a highly polished article at the end of the process.

30 In connection with the drying devices, it is my object to provide means whereby it is not necessary to lift out the articles before they are dry, but in which the heat of the machine, together with the moisture on the 35 glasses and such steam as is carried along with them will provide a perfect drying without leaving stains or spots, this drying not being in a strong current of dry air, but subject to heated air and consequent 40 moisture, to the proper degree necessary for a perfect product.

Another object of my invention is to provide in connection with a series of tanks, pumps and spray heads for a condenser system, which provides a certain quantity of 45 pre-heated water to one of the tanks and condenses away the vapor rising from the spray heads. This condenser system enables me to install my device in the finest confectionery shops without resulting in unpleasant 50 odors, or excessive humidity and heat.

In connection with the spraying system I provide a novel form of sprayer which is 55 quickly assembled and disassembled to clean out the nozzles or spray heads, and the entire

spray boxes containing the heads may be quickly set in place and removed without threaded fittings or the like.

In order to make my machine fool-proof, I provide for automatically stopping the 60 conveyor movement when a carrier has reached the drying and delivery compartment, in addition to the timing devices which provide proper intermittent motion from compartment to compartment. 65

In between each spraying chamber I provide a novel form of non-corrosive, metallic screen, which is lifted out of the way by the carriers or baskets.

The above noted objects and other advantages to be noted I accomplish by that certain construction and arrangement of parts to be hereinafter more specifically pointed out and claimed. 70

In the drawings,

75 Figure 1 is a central longitudinal section through the device.

Figure 2 is a section taken vertically, across any one of the compartments with the 80 operating devices omitted.

Figure 3 is a section on the line 3—3 of Figure 1 with the operating devices for the basket omitted.

Figure 4 is a detail longitudinal vertical section showing the article basket and the 85 sprayer and curtain devices.

Figure 5 is a top plan view of the casing of the machine showing the transferring devices or jump bar elements, the top being 90 removed from the machine.

Figure 6 is a detail, central longitudinal vertical section of the parts shown in Figure 5 with the spray heads removed.

Figure 7 is a vertical cross section of the machine showing the operating devices for 95 the jump bar, taken on the line 7—7 of Figure 5.

Figure 8 is a section taken on the line 8—8 of Figure 5 showing the jump bar.

Figure 9 is a plan view of the gear box 100 and jump bar energizing devices.

Figure 10 is a section on the line 10—10 of Figure 9.

Figure 11 is a section on the line 11—11 of Figure 9.

Figure 12 is a section on the line 12—12 of Figure 9.

Figure 13 is a section on the same line as Figure 12 with the parts in unclutched 105 position.

Figure 14 is a detail side elevation partly broken away showing the timing and clutch operating devices.

5 Figure 15 is a perspective view of the article carrying basket.

Figure 16 is a perspective view partly broken away of the spray device.

10 Figure 17 is a section like Figure 2 but on a larger scale.

15 The frame of the device comprises outside standards 1 and an inner row of standards 2, which support the tanks and spray devices along one side. The frame has top bars 3 and an insulated cover 4, preferably of sheet metal filled with mineral wool. The insulation need not extend over the receiving and delivery compartment.

20 On top of this cover, which may be in sections so as to be easily made and handled, is a counter-board 5, which provides a space on which to set the articles to be washed and the cleansed and dried articles when they are finished, and a convenient support for installing the articles in the baskets which carry them through the machine.

25 Mounted along the frame 1 on one side and the inner frame 2 on the other, are a set of plates 6 arranged to form water retaining tanks. The sides of these tanks extend from a point above the base sheet 7 of the frame so as to give clearance for the operating shaft and piping to the top of the machine, but the partitions 8 between them extend no further up than the traveling basket supports.

30 Hung from suitable cross pieces 9 are a series of curtains (four in number for a three compartment machine), which are made up of strips 10 of non-corrosive metal, such as brass, hinged together at 11 to make up a flexible flap that depends to the basket supports and lies in a slanting position against side bars 12 secured on the inner walls of the sheets 6. These curtains extend clear across the spaces above the tank partitions and are suitably weighted so that they will fall by gravity against the slanting bars and will act to sub-divide the spaces above the tank partitions into spray chambers.

35 For convenience I have noted the tanks in order as A, B, and C, and the spray compartments above the tanks by 1^A, 1^B, and 1^C. Of these, as will be noted, the first tank or tank A contains a sterilizing solution usually of lye and water in proper proportions, the tank B contains hot water, and the tank C contains hot water. As will be noted, the 40 number of tanks may be increased in certain cases and hence are not essential.

45 Across the space above the water level of the tanks and above the space required by the baskets in their travel, are cross pieces 13, which serve as supports for the spray devices, same being merely set in place and

not otherwise attached, due to the special construction to be noted.

50 The articles are carried through the machine in baskets 14 having foraminated sides and base and side handles 15, which, as shown, extend from end to end of the baskets and high enough above the bases thereof to lift the curtains clear of the articles in the baskets. The sides of these handles slope at a small incline to readily move the curtains.

55 In the baskets shown there is a cross strip 16 of foraminated structure into which glass tumblers may be set to hold them firmly during spraying, and the baskets are made 60 of wire of non-corrosive character, suitably woven in an open-work structure.

65 On the base of the baskets, at the four corners, are bifurcated fittings 17 and extending along the machine from end to end are angle bars 18, which are engaged by these bifurcated fittings, to hold the baskets 70 slidably in place, but against being lifted or jarred in any respect due to the operation 75 of the machine.

80 At the receiving compartment, noted at R, and the delivery compartment, noted at D, there are additional strips of metal 19 lying just under the flanges of the angle bars to form a double slideway therewith. The flanges of the angle bars are cut away 85 at one side as at 20 to permit the operator to tip the fittings of the basket into place over the flange of the bar at one side and drop them against the under support where the cut-away portions are located, thereby seating the basket quickly and easily into engagement with said flanges onto which it 90 rides on the cut-away side as soon as movement is started. The lifting of the baskets 95 out is accomplished by reversing the steps above noted.

100 In the compartment D is a base piece 21, which closes this compartment off from the body of the machine. The compartment R has also a base piece 22, and the side walls 6 forming the tank and spraying compartments are formed with glass fronts at the spraying point as at 23, with the compartments R and D left open at the one side of the machine for easy insertion and withdrawal of the baskets. The outer wall of the structure, where the double vertical frame is provided, is entirely closed off by a sheet of metal 24, which is insulated with asbestos, and hung from this side sheet are a series of electric bulbs 25, which shine through small glass windows 26 set into the inner walls 6 adjacent to them.

110 From the above it may be observed that the structure is entirely closed except for insertion and withdrawal of the articles to be washed, and that the operator or others may see the spraying operation.

115 120 125 130 The escape of humid, heated air through

the receiving compartment is prevented by the curtain closing off the spray chamber A, which is true also of the delivery compartment. However, in order to get a supply 5 of warm air for drying in the partially enclosed delivery compartment, I form a duct of sheet metal as at 26^a, and direct it from the lower portion of the interior of the machine to the delivery compartment 10 through an orifice 27 in the base piece thereof, thereby carrying the air warmed by the tanks into the said compartment.

The water-circulating and condenser system.

15 The various tanks have pipes 28 extending down therefrom and up into the middle of them at the inside. They have also pipes 29 extending down from the bases thereof. These pipes run to heating coils, which are 20 not shown, but will be like any water heating coil, except that for the compartment A, the heat may be less than for the other two compartments.

Extending into connection with the pipes 25 29 from each tank are a series of independent pipes 30, which come from a common cold water pipe 31 at the delivery end of the machine.

The pipes 30 are controlled by valves 32, 30 so that the flow to each tank may be controlled and from the base of each tank extends a pipe 33, which runs to a water gauge 34 located adjacent the valves, one gauge for each tank.

35 By this means the water for each tank comes into the pipes 29, and thence by a simple thermo-siphon action down into the coils and back through the other pipes 28.

The electric motor 35, set beneath the delivery compartment, has its shaft 36 extended clear across the machine to a gear box 37 at the other end. Set along this shaft are a series of rotary pumps 38, one for each tank. Each tank has a pipe extending from 40 its base into a pump, and from the pump a pipe 39 extends up through the space formed by the double frame parts, and is equipped with connections 39^a extending through the side walls 6 just above the level of the lower spray device supports, and just above the upper spray device supports. The inner walls 6 are equipped with plates 39^b into which these fittings extend, so that holes are formed into which water is pumped from 45 each tank above and below the basket supporting bars.

The spray devices are formed of hollow boxes 40, of suitable non-corrosive metal, having tubular extensions 41 from one side thereof, which are equipped with rubber caps 42 adapted to fit into the water holes.

50 The spray sides of each box are formed with holes therein into which are set spray heads 43 of disk-like form and having holes 55 therein to form water jets. The other sides

of the boxes are formed with lugs 44 extending from the inside thereof, which are threaded to receive screws 45, which engage and pass through the spray heads and may be quickly screwed into the lugs, there- 70 by holding the heads firmly in the holes.

This construction is easy to manufacture and easy to take down and clean. The heavy box devices are merely set on the supports with the rubber caps set into the 75 water holes above noted. No other connection is necessary for serviceable water-tight connection, and their weight will keep them solidly in place. To clean the spray heads, the operator merely lifts out the boxes and 80 unscrews the retaining screws for the heads, after which they may be lifted out.

For washing glass tumblers or other hollow ware it will be noted that the spray heads send sprays of hot water at the articles 85 from both sides, and thoroughly dash all dirt and grease therefrom.

A condenser 46, of any desired type, is mounted at the receiving end of the machine, and the air conduit portions thereof, as at 90 47, communicate with a duct 48. From the common cold water pipe of the tank-filling devices there is a fourth connection with suitable valve as at 49, from which water runs continuously (under ordinary conditions) 95 into the water portions 50 of the condenser.

From the condenser the cooling water passes by a pipe 51 to the tank C and from the well 52 of the condenser the water runs 100 through a pipe 53 to a trap 54 connected to the drain.

The heated air and steam from the various spray chambers is subject to a draft and suction imparted by a fan 55 driven by chain 105 and sprocket (preferably) from the motor shaft. This fan has a pipe 56 from its blowing end directed to a discharge 57 at the delivery end of the compartment 1^c. A duct 58 opens into the inner side wall of the spray compartment 1^a, and from thence runs to the air ducts of the condenser.

Thus the steam and moisture-laden air from the tanks does not get into the room where the machine is located, but instead 115 is condensed by incoming cold water, thereby heating the water, which may be used, in the last tank. The suction pipe into the fan extends from the trap 54 to the blower, as indicated at 59.

To drain the machine the user will use the pipes 29 and drain in the basement or wherever the heating coils are located. My machine provides no heating devices in immediate connection therewith, due to my utilization of the thermo-siphon principle. 125

The warm air passing up into the delivery compartment gains its heat from contact with the heated tanks and pipes, and due to the fact that the articles are delivered in a 130

mainly closed compartment, with heated air in it, the moisture carried by the articles is dried in air which is partially moist, so that a fine polish is given the articles and same 5 is quickly dried, whereas if the articles were to be removed at once to dry at room temperature, the moisture would collect in spots, and when dry leave a film of mark on the article requiring it to be wiped by a towel.

10 *The intermittent conveyor system.*

It will be remembered that the tank A is provided with a lye solution for sterilization of the articles to be washed, while the remaining tanks have merely hot water therein.

15 In moving the baskets containing the articles to be washed along the ways, therefore, it is necessary to hold the basket a sufficient interval in the presence of the lye solution to permit the sterilization to occur, say, with lye strength which I find to be satisfactory, for the period of one minute.

20 I must accordingly move the basket intermittently and time the movement for the necessary space.

25 The drive for the moving devices comes from the motor shaft heretofore noted, which passes into a gear case for this purpose. The conveyor or moving devices comprise two jump bars or reciprocating bars 30 60, which are supported on rollers 61 set into the side walls 6 below the basket supporting angle bars.

35 They carry gravity pawls 62, which when the bars are moved forward will hook behind the baskets and move them the distance of the bar movement, and when the bars are retracted will pass under the next basket and engage its end ready for moving it along. 40 There are necessarily four sets of pawls, one set for each step-by-step movement of the baskets.

45 At the receiving end of the machine the rack bars are connected by cross pieces 63, and a pair of reversely turned frames 64 are mounted to extend inwardly of the cross pieces, forming cam-shaped openings 64a. A bar 65, having rack teeth cut along both sides thereof, is set under the cross pieces and held against dropping away by means of cross strips 66, on which the bar rests but is free to slide.

50 On the upper side of the bar are two rollers 67, which extend into the cam pockets formed by the frames 64. A shaft 68 driven from the gear box extends up through the base plate of the receiving chamber and has a gear 69 thereon, which meshes with the rack.

55 60 This gear is driven in only one direction but it will travel along one side of the rack bar and thence around its end and back along the other side. This action is permitted by the special mounting of the rack bar permitting its ends to move through a

cam path freely. It will be noted that this movement completely around the rack bar comprises one complete cycle of movement of the jump bar devices.

When the jump bars return to their normal position they strike a lever 70 pivoted in the machine, which lever operates through a link 71, the clutch in the gear box, as will be noted. When a basket reaches the delivery and drying compartment it strikes a lever or trigger 72 pivoted to lie across the said compartment.

70 75 This trigger through a link 73, secured to an arm on the shaft 74 that supports it, inhibits the operation of the timing or automatic clutch throwing device.

75 80 The gear case carries within it a worm 75 meshing with a worm gear 76 on a shaft 77. The shaft 78 has a small worm 78a meshing with a worm wheel 79, this latter being the 85 timing wheel.

85 90 The shaft 77 on its end opposed to the worm gear 76 has a beveled gear 83, thus operating a beveled gear 82 carried on a stub shaft. This gear shaft carries a gear 81 95 which meshes with a gear 81a. Gear 81a drives the shaft 78 by means of the gear 81b thereon. The shaft 77 carries a swinging frame 84.

95 100 This frame 84 carries a shaft 85, which has a gear 86 meshing with the gear 83 while movable in a planetary manner with relation thereto.

100 105 It also carries a worm 87, and its frame is connected to a toggle 88. This toggle is on a rock shaft 89 at its other end, such that when the rock shaft is moved the toggle shifts the worm 87 upwardly or drops it down, the upward movement bringing the toggle past the vertical.

105 110 When the worm is forced up it meshes with a worm wheel or gear 90 on the driving shaft 91, this shaft being the support for the timing gear 79 also. The drive shaft at its end has a large gear 92 meshing with the gear 93 of the vertical shaft that operates the rack bar gear, heretofore mentioned.

110 115 Against the face of the timing gear is a clutch tripping member made of two disks 94 spring hinged together at 95 and mounted loosely over the shaft 91. The timing gear has a series of holes 96 formed in it, and the outer of the two disks 94 carries a pin 97 which passes through the inner member and engages one of the said holes. The 120 spring hinge serves to force this pin into mesh where the mechanism permits the movement.

120 125 The outer disk carries a tongue 98, which upon revolution of the shaft 91 comes into a position to strike a lever 99 on the rock shaft 89, thereby throwing upwardly the driving worm that forms the clutch, as above noted.

125 130 The lever energized by the return move-

ment of the jump bar devices has its link connected to a weighted lever 100 pivoted in the gear case, which lever has a hook 101 thereon and suitably pivoted as at 101^a. When the lever is moved the hook engages and pulls over a disk 102 mounted on a slide rod 103 in the case. The slide rod has an end which strikes against a second finger 104 on the rock shaft 89, thereby opening the clutch by exerting a lowering force and bending the toggle that holds up the worm.

Thus the time wheel operates the device for throwing the clutch in and the jump bar trip lever operates the clutch to throw it out.

The trigger 72, operating its shaft 74 and thence the rigid link 73 in the delivery compartment of the machine acts to prevent the operation of the clutch tripping member of the timing gear by spreading the two hinged disks and removing the pin on the outer one from mesh in the holes of the time gear proper. Thus the link from this trigger engages an arm 105, which carries a knife piece 106, said knife piece lying in a position to enter between the two disks as they come around and force them apart. A foot treadle may control this also through a link 105^a.

Thus when a basket of glasses or what not comes into the delivery compartment, the next regular operation of the jump bars will be prevented, while the pumping of water, and the rest of the action of the machine will go on until the basket is removed, whereupon the spring 107 will retract the trigger link and the time gear, and the clutch operating member again pinned to it will throw in the clutch and the feed will begin again.

The slide rod which is controlled by the jump bar trip is returned to normal position as soon as the jump bars start to move by a spring 108 on the jump bar lever. This throws the operating end of the hook down behind the disk on the slide and since the hook cannot swing further than the position shown in Figure 13, the clutch may close and the slide rod move to running position of the machine without the hook interfering therewith, while the stop pin 109 directs the hook into its engaging position behind the disk (Figure 12) as soon as the jump bars start to move.

It is not believed to be necessary to describe the operation of the machine as a whole. It is evident that the proper timed motion of the baskets is gained through a mechanical timing device, although this might be electrical, if desired.

The machine may be made to operate more quickly than one basket per minute, by using four tanks, two of which are filled with lye

solution and the basket permitted to stay one half minute in each lye tank.

The gearing devices might, of course, be modified, and the ones described are merely the preferred ones, and furthermore the machine need not be used for glass tumblers only, although in the particular design illustrated and described it is specially adapted for use with hollow ware.

Among other features of my invention I lay particular stress on the fact that the machine can be installed in a confectioner's shop or drug store, and left in plain view of the customers, without heating up the room, and with the result of assuring the customer of clean and fully sterilized glasses, cups or bottles, as the case may be.

The freedom from jar and rattling due to the baskets and slideways is a valuable feature, as is the fool-proof arrangement at the delivery and drying compartment.

I have not attempted to describe various modifications of my present design of machine, but do not wish this to be used as indicating that I do not desire to include within my invention, as expressed in the following claims, the full range of usual mechanical equivalents for the parts named. 90

Having thus described my invention, what I claim as new and desire to secure by Letters Patent, is:—

1. In a machine of the character described, the combination of a casing, water tanks 95 therein, spray heads located above the tanks, and means for forming compartments of the space above the tanks comprising depending screens formed of metallic plates hinged together and secured to the casing so as to 100 depend and act as a curtain.

2. In a machine of the character described, the combination of a casing, movable closures forming compartments therein, spray devices in said compartments and a support 105 for a container, and a container formed of foraminated material and having side handles, said handles being adapted to contact with the movable closure, and having a height equal, at least, to articles placed in 110 said container.

3. In a machine of the character described, the combination of a casing, depending screens forming compartments in said casing, spray devices in said compartments a 115 support for a container within said compartments, and a container of foraminated material adapted to engage said support, said container having side handles extending upwardly at the corners thereof, and 120 thence at a height, at least, equal to the articles to be placed in said basket across the sides thereof.

LOUIS F. UTZ.
